RADIO SIGNALING APPARATUS

Filed Nov. 14, 1927

UNITED STATES PATENT OFFICE

GEORGE OWEN SQUIER, OF WASHINGTON, DISTRICT OF COLUMBIA

RADIO SIGNALING APPARATUS

Application filed November 14, 1927. Serial No. 233,010.

This invention relates to radio signaling apparatus and more particularly to the provision of means for enabling the utilization of power lines, such as telephone wires, electric light wires, etc. for the absorption element or antenna of radio receiving systems.

One of the objects of my invention is to provide a simple, economical and efficient attachment to enable the utilization of existing lines as an antenna.

A further object of the invention is to provide a device of this character to overcome the difficulties incident to the effect on radio receiving apparatus of disturbing electrical effects present in such lines.

Further objects of the invention will appear more fully hereinafter.

The invention consists substantially in the construction, combination, location and relative arrangement of parts, as well as in the circuit arrangement employed therein, or as shown in the accompanying drawing and finally pointed out in the appended claims.

Referring to the drawings,—

Figure 1 schematically illustrates one arrangement embodying the subject matter of my invention.

Figure 2 is a similar view showing a modified arrangement.

Figure 3 is a similar view showing a further modification.

Figure 4 is a view partially in vertical cross-section of a plug embodying my invention.

The same parts are designated by the same reference characters wherever they occur throughout the several views.

While many arrangements have been heretofore proposed, some of which have gone into use of employing power lines, such as telephone wires, electric light wires, power transmission lines, etc., to act as the absorption element or aerial for radio signals, or as the carrier of radio frequency currents of a wired-wireless system, no suitable provisions were made to eliminate disturbances from the line. In addition to the natural static or electrical disturbances on such lines, there are many so-called "man-made" static effects which increase the disturbing

effect of such lines on the radio apparatus employed in connection therewith. To mention only a few in common use, there are employed today on power lines of this character oil burning heaters, dental apparatus, elevators and medical machines, and a large variety of other apparatus. Efforts have been made to diminish this form of disturbance and interference by the employment of choke coils inserted in the line and by-pass condensers. Apparatus generally employed for this correction is of the audio frequency type. That is, the capacities are measured in micro-farads and the choke coils are required to carry the power of the line. In other words, up to the present time such correction, where correction is in fact secured is made by robust traps and not by means of radio apparatus.

The present invention relates to the provision of a small inexpensive but highly efficient device employing radio principles for accomplishing this result, where the accomplishment thereof is effected at the radio apparatus. It is among the special purposes of my present invention to provide a plug which can be inserted in a standard socket, for example, in a standard electric light socket, or service outlet, which will permit the clearing out of all disturbances, which are now on such power lines, due to its regular electrical load and cleaning out the line disturbances thoroughly, so that the high frequency current itself is sorted out and delivered to the receiving set.

In accordance with my invention instead of having a plug such as has heretofore been employed consisting of two small blocking condensers incapable of effectively absorbing energy, I provide a plug employing a variable transformer, which is suitably designed to drain off through the primary all disturbances on the line, which are not permitted to enter the secondary of the transformer due to the loose coupling employed.

Referring to the drawings, in which I have diagrammatically illustrated the principle of my invention, reference character 1 designates a power line which in the particular form shown consists of a two-wire electric

light circuit for lighting lamps, diagrammatically illustrated at 2. The radio apparatus in this instance, a radio receiving set is diagrammatically illustrated at 3. The power line is connected through a condenser 4 to ground 5 through a primary coil 6 of a transformer, the secondary coil 7 of which is adjustably coupled therewith, the terminals of the said secondary coil being connected to the radio receiving apparatus 3.

In Figure 2, a modified arrangement is shown wherein instead of connecting the power line through a condenser 4, two condensers 8 and 9 are connected between the wires 1 of the power line and the tap connection for the radio receiving apparatus 3 is made between the two condensers 8 and 9.

In Figure 3, the condensers 8 and 9 are connected through two primary coils 10 and 11 connected in series, the ground connection 5 being provided between the two coils 10 and 11. In this arrangement it is not necessary to ground the radio receiver, the terminals of which include two primary coils 12 and 13, which are preferably wound in opposite directions, so as to produce electromotive forces of the same direction from the primary coils 10 and 11.

The couplings of the transformers are so designed as to permit the effective transfer of the high frequency signal energy to the receiver, but at the same time effectively blocking the transfer of disturbances which are generally of low frequency character. These transformers can be built very compactly and enclosed in a plug of the dimensions now in use and hereinbefore referred to.

For example, the standard electric light socket is illustrated at 21. The plug is formed in two parts. One part 20 screws into the socket and forms an electrical contact with one terminal therein. A wire 22 includes the primary coil and the condenser 4. The body of the plug 20 is provided with exterior threads as shown, over which fits the auxiliary body 23, which is adjustable thereon, so as to vary the coupling of the secondary coil 7 carried therein. In this way the couplings in these plugs could be adjustable for each locality to suit the particular frequency of the signals, which are received in that particular locality. The terminals of the transformer winding 7 are illustrated at 24 and may be included in a single cord, similar to a telephone cord, if desired.

While I have shown the arrangement of Figure 1 incorporated in a plug structure, it will be readily apparent that the arrangements of the other figures of the drawing, as well as many modifications thereof, which will suggest themselves to those skilled in the art may equally well be incorporated in single plug structures.

It will now be seen that the high frequency

signals collected or guided by the power lines together with the relatively lower frequency static effects are discharged from the power lines through the ground, the high frequency or signal currents being induced in the secondary coil of the transformer associated with the primary coil included in the ground path. The adjustable coupling between the transformer coils permits a control of the efficiency of elimination of the disturbing effects, which will be largely dependent upon the particular locality, the nature of the disturbing effects, etc.

Many modifications and changes in details will readily occur to those skilled in the art without departing from the spirit and scope of my invention as defined in the claims and I, therefore, desire to have the foregoing description regarded in the illustrative sense rather than in a limiting sense. It will likewise be understood where I have herein and will hereinafter refer to power lines I desire to have this term include all such lines as are employed in electric lighting systems, transmission of power, telegraph, telephone and in general all systems which employ lines for the conduction of the electric current therefor.

Having now set forth the objects and nature of my invention and having shown and described structures and arrangements embodying the principle thereof, what I claim as new and useful and of my own invention and desire to secure by Letters Patent is:—

1. Means for utilizing a power line provided with a standard socket for radio reception comprising a plug for insertion into said socket, a transformer included in said plug, means for connecting the terminals of one winding of said transformer to a radio receiving set, and means forming part of said plug for adjusting the coupling between the windings of said transformer.

2. Means for utilizing a power line provided with a standard socket for radio reception comprising a plug for insertion into said socket, a transformer included in said plug, means for connecting the terminals of one winding of said transformer to a radio receiving set, means forming part of said plug for adjusting the coupling between the windings of said transformer, said means varying the position of one winding of the transformer relatively to the other winding thereof.

3. Means for utilizing a power line provided with a standard socket terminal for reception of radio signals comprising a plug adapted to be detachably inserted in said socket for electric connection with said power line and having a primary coil included therein and in said connection, a movable member carried by said plug and provided with a secondary winding for said transformer mounted therein and wires leading from

said plug, one from said connection and two from the terminals of the said secondary winding.

In testimony whereof I have hereunto set
5 my hand on this 3rd day of November, A. D.
1927.

GEORGE OWEN SQUIER.
